UNITED STATES PATENT OFFICE.

HARRY STALL, OF ROCHESTER, NEW YORK.

GARMENT POCKET.

Application filed July 27, 1925. Serial No. 46,192.

The present invention relates to garment pockets and more particularly to the type in which the pocket proper is covered by a patch either upon the outside or inside 5 of the garment. An object of the invention is to so construct a patch that the pocket may expand. Another object of the invention is to provide a construction which will make it possible to sew the patch on 10 by unskilled labor, doing away with the hand felling used in patches heretofore employed.

To these and other ends, the invention consists of certain parts and combinations 15 of parts, all of which will be hereinafter described: the novel features being pointed out in the appended claim.

In the drawings:—

Fig. 1 is a view of a man's coat equipped 20 with a pocket;

Fig. 2 is a fragmentary view of the inside of a lower corner of a coat showing the pocket patch;

Fig. 3 is a view showing the pocket patch 25 partially ripped from the pocket to expose the garment pocket;

Fig. 4 is an enlarged section on the line 4—4, Fig. 2;

Fig. 5 is a view of the garment equipped 30 with an outside patch;

Fig. 6 is a section through the construction shown in Fig. 5; and

Fig. 7 shows the same construction with the pocket expanded.

Referring more particularly to the embodiment of the invention, 1 indicates a garment which, in this instance, is a man's coat. This coat is only partially lined as 35 at 2 on its inner side. The garment is pro-

vided with the usual pocket slot 4 covered by an outside flap 5, the pocket 6, fastened in the usual manner, being suspended on the inner side of the garment. As this pocket, owing to the absence of the lining will other- 40 wise be exposed, it is customary to provide over this pocket a patch 3. Prior to this invention this patch has been secured to the inner face of the garment at its lower and side edges through a bellows arrangement,

50 which will permit the patch to move slightly away from the garment at its edges

when the pocket would be expanded. Such an arrangement required a hand felling operation and this necessitated the employment of highly skilled labor.

55

According to this invention a pocket patch is provided which can be secured in place by unskilled labor without any basting operation and without hand felling in the first instance, thus reducing the cost 60 of manufacture of the garment.

According to the embodiment of the invention illustrated in Figs. 1 to 4, inclusive, the patch 3 is formed of the same material as the main material of the garment and 65 has three of its edges extending beyond the lining 2 provided with a finishing strip or binding 7 which may be stitched on by the sewing machine before the patch is applied to the pocket. This patch is also pro-

70

vided with an L shaped slot 8, the walls of which are connected by bellows 9, said slot conforming to the bottom and one of the side edges of the pocket 6. This bellows arrangement can also be stitched on 75

the ordinary sewing machine before the patch is applied to the garment. After the patch is completed, it is stitched over the pocket by stitches 10 at its edges, the patch being extended under the lining 2. It will 80

thus be seen that the bellows is provided in the patch before the latter is secured to the garment and the edge of the patch is also finished before the patch is secured to the garment. All of this work may be done 85 by an unskilled workman on a sewing machine and the patch may later be secured to the garment by an unskilled workman without any felling operation.

90

In the embodiment of the invention illus- trated in Figs. 5, 6 and 7, the invention is shown in a garment having outside pocket patches. In this construction, the garment

1 has a patch 3^a of the same material as such garment, secured to its outer face over a pocket 6^a fastened to the garment in the usual manner. This patch 3^a is provided with a cut 8^a within its edges conforming substantially to the outline of the pocket. The edges of this cut are connected by a bellows 9^a which is formed of the same material as the patch. The edge of the patch 95

100

3^a is turned and seamed to the body of the garment in the usual manner as at 10^a.

From the foregoing it will be seen that there has been provided a pocket having a patch covering the same and formed with a bellows within its edges, thereby permitting the patch to be made independently of the garment and fastened to the garment by unskilled labor without any basting or 10 felling operation.

What I claim as my invention and desire to secure by Letters Patent is:—

In combination with a garment having a pocket, a patch covering said pocket provided with a cut within its edges, and a bellows connecting the edges of said cut to permit the expansion of the pocket patch said patch being secured to the garment between the bellows and the edge of the patch. 15

HARRY STALL.
